US00D822034S

(12) **United States Design Patent** (10) Patent No.: **US D822,034 S**
 Clymer et al. (45) Date of Patent: ** Jul. 3, 2018

(54) **DISPLAY SCREEN OR PORTION THEREOF WITH GRAPHICAL USER INTERFACE**

(71) Applicant: **Lutron Electronics Co., Inc.**,
 Coopersburg, PA (US)

(72) Inventors: **Erica L. Clymer**, Nazareth, PA (US);
Brian Michael Courtney, Bethlehem, PA (US); **Sanjeev Kumar**, Harleysville, PA (US); **Sandeep Mudabail Raghuram**, Emmaus, PA (US); **Richard M. Walsh, III**, Bethlehem, PA (US); **Jennifer Wong**, Breinigsville, PA (US)

(73) Assignee: **Lutron Electronics Co., Inc.**,
 Coopersburg, PA (US)

(**) Term: **15 Years**

(21) Appl. No.: **29/562,240**

(22) Filed: **Apr. 24, 2016**

(51) LOC (11) Cl. **14-04**

(52) U.S. Cl.

USPC **D14/485**

(58) **Field of Classification Search**

USPC **D14/485-495**

CLAIM

The ornamental design for a display screen or portion thereof with graphical user interface, as shown and described.

DESCRIPTION

The sole FIGURE shows a display screen or portion thereof with graphical user interface showing our new design. The dashed broken lines represent a display screen or portion thereof and form no part of the claimed design.

1 Claim, 1 Drawing Sheet
